(57) **CLAIM**

The ornamental design for a tie strap, as shown and described.

DESCRIPTION

FIG. 1 is a front perspective view of tie strap, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof, showing the tie strap in an alternative position.
The broken lines in the drawings depict portions of the tie strap, that form no part of the claimed design.
